EXAMINATION LIGHT FIXTURE

Marcus Bodian, Los Angeles, Calif., assignor to Sunbeam Lighting Company, Los Angeles, Calif., a limited partnership

Filed Apr. 24, 1961, Ser. No. 64,855

Term of patent 14 years

(Cl. D48—20)

FIG. 1.

FIG. 2.

FIG. 4.

FIG. 3.

FIG. 5.

FIG. 6

FIG. 1 is a front elevation of an examination light fixture showing my new design;

FIG. 2 is a top plan view thereof;

FIG. 3 is an end elevational view thereof as seen from the right of FIG. 1;

FIG. 4 is an end elevational view thereof as seen from the left of FIG. 1;

FIG. 5 is a perspective view thereof as seen from the left showing the light and arm in an alternate adjustable position.

FIG. 6 is an enlarged sectional view taken on the line 6-6 of FIG. 5.

The rear walls of the fixture and of the housing for the light member are substantially plain.

I claim:

The ornamental design for an examination light fixture, as shown and described.
